[57] CLAIM

The ornamental design for a combined table and multiple stool unit, as shown and described.

DESCRIPTION

FIG. 1 is an elevational perspective view of a combined table and multiple stool unit incorporating the invention;

FIG. 2 is a top view of the unit shown in FIG. 1;
FIG. 3 is a side elevational view along line 3—3 of FIG. 2;

FIG. 4 is a bottom view of the invention shown in

FIGS. 1-3; and

FIG. 5 is a side elevational view along line 5—5 of FIG. 2.

FIG. 1

FIG. 2

FIG. 3

FIG. 4

FIG. 5
